DESIGN FOR A HEATING-STOVE.

SPECIFICATION forming part of Design No. 20,972, dated July 28, 1891.

Application filed July 1, 1891. Serial No. 398,184. Term of patent 7 years.

To all whom it may concern:

Be it known that I, FRANCIS RITCHIE, a citizen of the United States, and a resident of Troy, Rensselaer county, New York, have invented a Design for a Wood-Stove, of which the following is a specification.

My design for a "wood-stove" is clearly illustrated in the accompanying drawing, representing the stove in perspective.

10 The main features of the design are the panels and scrolls on the body of the stove.

The base has a plain top and is supported by feet. The body of the stove has a front plate, on which are two panels, the lower panel being quadrangular in shape, and the upper panel has its upper edges rounded with a semicircular depression at the top. On the lower panel is a central rosette, from which extend on each side foliated scrolls. The 15 panel has a beaded border, as clearly shown in the drawing. The upper panel has also a beaded border, and on this panel are two S-

scrolls, and extending from the lower arm of each scroll are a series of scrolls of the character clearly shown in the drawing. On each side 25 of the panels, and extending from the base to the top, are two elongated panels composed of scroll-work. The side door has scroll-work in keeping with the scroll-work of the upper panel, and the space between the side door 30 and the top has scroll-work in keeping with the lower panel on the face of the stove. The top has a dome and an urn in keeping with the general design of the stove.

I claim as my invention— 35
The design for a stove, as described, and as shown in the accompanying illustration.

In testimony whereof I have signed my name to this specification in the presence of two subscribing witnesses.

FRANCIS RITCHIE.
